UNITED STATES PATENT OFFICE

HOWARD J. KERR, OF WESTFIELD, NEW JERSEY, AND JAMES E. TRAINER, OF BARBERTON, OHIO, ASSIGNEES TO THE BABCOCK & WILCOX COMPANY, OF BAYONNE, NEW JERSEY, A CORPORATION OF NEW JERSEY

STOKER

Application filed April 12, 1928. Serial No. 269,335.

This invention relates to an improvement in a construction of stokers, and more particularly in stokers of the chain-grate type. In stokers of that type, trouble has been experienced by the heating and consequent expansion of the grate. This heating will cause the lower run to sag, and it has been customary to tighten up the stoker to prevent this sagging. Then, when the stoker becomes cool, an additional tension is placed thereon which often causes undue strain.

According to the invention, we provide an adjusting means for taking up the sag in the grate and, at the same time so construct this adjusting means that it will yield when the stoker contracts, before undue strain is put upon the stoker.

In the accompanying drawings, in which we have shown selected embodiments of our invention;

Fig. 1 is a sectional view through a portion of a furnace and grate having our invention embodied therein, the showing of this figure being diagrammatic in character.

Fig. 2 is a horizontal sectional view through one end of a bearing for a stoker shaft, this view being taken on the line 2—2 of Fig. 3.

Fig. 3 is a section on the line 3—3 of Fig. 2.

Fig. 4 is a section on the line 4—4 of Fig. 2.

Fig. 5 is a section on the line 5—5 of Fig. 3.

Fig. 6 is a view similar to Fig. 2, but showing a different embodiment of the invention, this view being taken on the line 6—6 of Fig. 7.

Fig. 7 is a section on the line 7—7 of Fig. 6.

Fig. 8 is a section on the line 8—8 of Fig. 6.

Fig. 9 is a section on the line 9—9 of Fig. 7.

Fig. 10 is a view similar to Fig. 2, but showing a still further embodiment of the invention, this view being taken on the line 10—10 of Fig. 11.

Fig. 11 is a section taken on the line 11—11 of Fig. 10.

Fig. 12 is a section taken on the line 12—12 of Fig. 11.

Fig. 13 is another view similar to Fig. 2, but showing a still further embodiment which the invention may take, this view being taken on the line 13—13 of Fig. 14.

Fig. 14 is a section taken on the line 14—14 of Fig. 13.

Fig. 15 is a section on the line 15—15 of Fig. 14.

Referring to Fig. 1, we have shown there in a portion of a furnace having a hopper 1 from which coal is fed to the top run 2 of a chain-grate stoker. This stoker is of any usual form, and is merely shown diagrammatically in this figure. It will not be described in detail but, for the purposes of this application, it is sufficient to say that it is operated in the usual manner by sprockets supported on shafts at opposite ends of the stoker.

One of these shafts is herein diagrammatically indicated at 3, together with its adjusting mechanism 4. This adjusting mechanism is more fully shown in connection with the other figures of the drawings, and is used to move the bearing of the shaft along guides 5 which are indicated diagrammatically in Fig. 1.

Referring now to Figs. 2, 3, 4 and 5, we have shown therein a fixed member 6 at one end of the guides 5, this member being a part of the same frame as the guides. Secured in the fixed member and held against rotation therein, as by set screws, is a nut 7 in which is threaded an adjusting screw 8. In this form the screw is provided with a capstan adjusting head 9 which is drilled to form a recess for the thrust pin 10.

The bearing 11 for the shaft 3 has a recess 12 therein, within which is disposed a bearing member 13 which is connected to the thrust pin 10 by means of a shear pin 14 extending through both the bearing member and the thrust pin.

By this means, when the grate expands, the sag therein may be taken up by turning the capstan headed screw which will result in moving the bearing 11 lengthwise of the grate in the guides 5. While we have shown only one adjusting screw and one bearing, it will be understood that similar adjusting means may be provided for as many bearings of the shafts 3 as may be found convenient. For example, if the shaft has two bearings

at opposite ends thereof, two adjusting means will probably be used.

When the grate cools, however, a shrinkage takes place, and the adjusting means should be again operated to permit this shrinkage. If this adjustment is not made, however, due to oversight or carelessness, the shear pin is purposely made relatively weak, so that it will yield and break before any part of the grate. The shear pin may be easily replaced before the grate again becomes heated enough to require adjustment.

Referring now to Figs. 6, 7, 8 and 9, the adjusting screw 15 has its end 16 squared and fitting within the bearing 11, and thus held against rotation. The thrust in this form is taken by the capstan nut 17 which is threaded upon the screw 15, and this nut bears against a collar 18 received in a recess 19 in the fixed member 6.

The collar is secured in the fixed member by means of shear pins 20, and it will be noted that the recess 19 is of such a size that when the shear pins break, the collar may have movement toward the left in the recess. The front face of the fixed member 6 is also provided with a recess 21 to receive the nut 17 upon breaking of the shear pin, and in this form the recess is sufficiently deep so that the nut cannot again be turned to adjust the screw until the screw has been moved forwardly and the shear pins put in position, the holes in the nut being sufficiently covered by the walls of the recess to prevent insertion of a tool therein.

Referring now to Figs. 10, 11 and 12, the adjusting screw 22 is provided with a capstan head 23 which has a recess 24 within which is disposed the thrust pin 25. This thrust pin is secured to the head by means of the shear pin 26 which, as in the other forms, is adapted to yield before any part of the grate. When yielding takes place, the holes in the head are covered by a guard 33, preventing turning of the head until a new shear pin has been installed.

In Figs. 13, 14 and 15, the adjusting screw 27 has a squared end 28 disposed in a recess 29 in the capstan nut 30, which has a projection 31 in a recess in the bearing 11. The squared end 28 is secured to the nut 30 by means of the shear pin 32.

We claim:

1. In a chain-grate stoker, a movable bearing for a shaft of the stoker, means to adjust said bearing to take up slack as the grate expands, and a relatively weak connection between said bearing and adjusting means and adapted to fracture as the grate shrinks if proper adjustment of the bearing is not made to relieve the strain on the adjusting means.

2. In a chain-grate stoker, a movable bearing for a shaft of the stoker, means to adjust said bearing, a relatively weak connection between said bearing and adjusting means and

adapted to yield if proper adjustment of the bearing is not made to relieve the strain on the adjusting means, and means preventing operation of said adjusting means after yielding of said connection.

3. In a chain-grate stoker, a bearing for a shaft of said stoker, said bearing being movable with the shaft lengthwise of the stoker, an adjusting screw to cause movement of said bearing to take up slack as the grate expands, and a shear pin between the bearing and the screw, yieldable upon undue strain occurring in the stoker as the grate shrinks.

4. In a chain-grate stoker, a bearing for a shaft of said stoker, said bearing being movable with the shaft lengthwise of the stoker, a fixed member adjacent said bearing, an adjusting screw supported by said member operable to cause movement of said bearing to take up slack as the grate expands, and a shear pin between said bearing and member for the purpose set forth.

5. In a chain-grate stoker, a bearing for a shaft of said stoker, said bearing being movable with the shaft lengthwise of the stoker, a fixed member adjacent said bearing, an adjusting screw supported by said member operable to cause movement of said bearing to take up slack as the grate expands, and a shear pin connecting certain of said members yieldable upon undue strain being exerted on said stoker as the grate shrinks.

6. In a chain-grate stoker, a bearing for a shaft of said stoker, said bearing being movable with the shaft lengthwise of the stoker, an adjusting screw to cause movement of said bearing to take up slack as the grate expands, a thrust pin carried by said screw and engaging said bearing, and a relatively weak shear pin connecting the screw and thrust pin yieldable upon undue strain being exerted on said stoker as the grate shrinks.

7. In a chain-grate stoker, a bearing for a shaft of said stoker, said bearing being movable with the shaft lengthwise of the stoker, an adjusting screw to cause movement of said bearing, a thrust pin carried by said screw and engaging said bearing, a relatively weak shear pin connecting the screw and thrust pin, and means preventing operation of said screw when said shear pin is broken or displaced.

8. In a chain-grate stoker, a bearing for a shaft of said stoker, said bearing being movable with the shaft lengthwise of the stoker, a fixed member adjacent said bearing, an adjusting screw supported by said member, means to operate said screw, a relatively weak connection between the fixed member and the bearing, and means preventing operation of said screw when said shear pin is broken or displaced.

9. In a chain-grate stoker, a bearing for a shaft of said stoker, said bearing being movable with the shaft lengthwise of the stoker, a fixed member adjacent said bearing, an ad-

justing screw supported by said member, an adjusting head on said screw, a thrust pin disposed in a recess in said head and in engagement with said bearing, and a shear pin connecting said head and said thrust pin for the purpose set forth.

10. In a chain-grate stoker, a bearing for a shaft of said stoker, said bearing being movable with the shaft lengthwise of the stoker, a fixed member adjacent said bearing, an adjusting screw supported by said member, an adjusting head on said screw, a thrust pin disposed in a recess in said head and in engagement with said bearing, a shear pin connecting said head and said thrust pin, and a guard on said bearing movable, when said shear pin breaks, into position to prevent operation of said head by a tool.
